UNITED STATES PATENT OFFICE

2,400,591

DIAMOND DESIGN JEWELRY CHAIN

Nicholas Nanasi, New York, N. Y.

Application October 11, 1945; Serial No. 621,676

2 Claims.

(Cl. 59-80)

This invention relates to jewelry chains of the flexible type, and has for its main object to provide a chain of this character, which will be more attractive in appearance than such mesh type jewelry chains made or proposed heretofore.

Another object of my invention is to provide a jewelry chain as characterized hereinbefore, which is composed of pivoted link elements, exposed portions of the link members providing a new mesh design, the adjacent edges of such link portions being closely drawn to one another, and the chain still being flexible.

Still a further object of my invention is to provide a flexible mesh jewelry chain which will be adapted for comparatively easy and inexpensive mass manufacture.

Further objects of this invention will be apparent as the specification of the same proceeds. In the drawing forming a part of this specification and accompanying the same:

Fig. 1 is a plan view of a portion of mesh type jewelry chain, made according to one form of my invention;

Fig. 2 shows a blank used in manufacturing this form; and

Fig. 3 is an end view of a portion of the ready chain indicating a link element prepared and in position to be added thereto; this figure is on a larger scale than Figs. 1 and 2.

Referring now to the drawing, more in detail, by characters of reference, the numeral 10 indicates my novel mesh jewelry chain, in general, the same being composed of blanks, generally indicated at 11. These blanks will be cut out of an appropriate thin sheet of material as usual for such chains, like gold, and will have a central elongated web or main body portion 12, at the two sides of which will be formed diamond shaped arms 13 being alternately placed at the two sides of the central body portion 12. The adjacent corners 14 of the diamond shaped arms may meet, indeed, there the material of the original sheet may be left intact during the operation of cutting the blank 11 from such sheet.

The outer corners of the diamond shaped arms are continued in a comparatively long portion 15, which will be used as a locking or hook device for the chain.

When manufacturing the chain, a blank 11 will be bent into the shape shown in end view in Fig. 3, and generally indicated by the numeral 11a. When the blank is bent in said shape, as will be explained more in detail presently, it will be added to the earlier prepared portion 10a of the chain 10, in the manner indicated in Fig. 3.

It will be seen that the arm 13a of the bent blank 11a, forming the link to be next added to the chain, will be bent at an obtuse angle with reference to the body portion 12a, the angle being smaller than usual with other mesh type chains formed of links in a somewhat similar manner. The arms 13a will be almost rectangularly set as against the body portion 12a.

The outer ends 15a of the arms, being the locking or hook portions thereof, as will be understood and shown presently, will be bent very strongly rearwardly almost in parallelism with the main portion 13a of the arm.

A comparatively small space, indicated at 16, will be left between the inwardly turned locking portions 15a at the two sides of the link member, and said link member will be applied on the previously prepared portion 10a of the chain, by being pushed over thereof through said space 16, as indicated in Fig. 3, by the arrow 16a.

After pushing the new link over the existing portion of the chain to a desired predetermined extent, the arms at the two sides of the link will be pressed inwardly, as indicated by the arrows 17 and 18, by an appropriate tool or die, as it is well known in this art. Upon such inward pressing, the arms will take up a generally full right angular position against the body portion 12a, forming the upper and lower planes or surfaces 19 and 20, respectively, of the ready chain. Upon such flat pressing of the arm 13a, the outer ends 21 of the rearwardly turned locking extensions 15a will press against the body member 12b of the link 11b, being the last link in the chain previously finished, and will pull the body portion 12a, of the link 11a to be added towards the ready chain, as indicated by the arrow 22, and upon the final pressing down of the arms 13a into the outer planes of the chain, the links will be closed upon one another to such an extent, that the edges 23 in the triangular part of the diamond 13, will meet, as indicated in Fig. 1, so that a beautiful pattern of diamond shaped elements will be shown on the surface of the chain, with very small, or practically no spaces between, the diamond shaped elements, and fine division lines between them, but the chain will still be flexible to a limited extent sufficient to form an adjustable bracelet, or the like, from said chain.

It also will be seen that upon such a pulling of the new link 11a over the last earlier link 11b and pressing its arms 13 into the respective planes 19 and 20 of the chain, the front, substantially half triangular, portion 24 of the arms 13 of the new link 11a will fit into the substantially trian-

gular and identical spaces 25 in the earlier finished link 11b, and, vice versa, the rear half triangular portion 26 of the earlier link 11b will fit into the spaces 27 of the new link 11a.

I may remark that other shapes than the diamond shape shown in the drawing may be given to the arms 13, and a chain constructed according to my invention, with such geometric contour for the arms and the spaces therebetween, and upon such drawing close of the links of the adjacent arms, the respective portion of the arms in one link will exactly fit into the corresponding spaces in the arms in the other links, and patterns of other designs than a diamond shape may be formed in the ready chain in such manner.

What I claim as new and want to protect by Letters Patent of the United States, is:

1. A jewelry mesh chain, comprising pivotally connected link elements transversely set in the chain in a side by side relation, each link having an elongated flat body portion set perpendicularly to the plane of the chain, a plurality of arms at the upper and lower edges of the body portions of said links pointing in the same direction but being set alternately in the adjacent links, the main portion of each arm being of diamond shape with adjacent corners thereof substantially touching one another, each arm having front and rear substantially triangular half portions, and similar, substantially triangular, front and rear spaces therebetween, the triangular front portions in the arms of a later link fitting into the respective triangular rear spaces between the arms of the adjacent preceding link in the chain, and, vice versa, the rear portions of the arms in the preceding links fitting into the front spaces of said later links, the outer ends of the arms having inwardly bent locking portions projecting into the chain in the rear spaces between the arms of said preceding link.

2. A jewelry mesh chain, comprising pivotally connected link elements transversely set in the chain in a side by side relation, each link having an elongated flat body portion set perpendicularly to the plane of the chain, a plurality of arms at the upper and lower edges of the body portions of said links pointing in the same direction but being set alternately in the adjacent links, the main portion of each arm being of diamond shape with adjacent corners thereof substantially touching one another, each arm having front and rear substantially triangular half portions, and similar, substantially triangular, front and rear spaces therebetween, the triangular front portions in the arms of a later link fitting into the respective triangular rear spaces between the arms of the adjacent preceding link in the chain, and, vice versa, the rear portions of the arms in the preceding links fitting into the front spaces of said later links, the outer ends of the arms having inwardly bent locking portions projecting into the chain in the rear spaces between the arms of said preceding link, said locking portions of the arms being bent curved rearwardly towards the body portions of the links whereby in setting said link portions into the spaces along the body portions of the adjacent preceding links in the chain, and pressing the arms of the link to be added flat into the upper and lower planes of the chain, said rearwardly curved locking portions will engage the body portion of said adjacent earlier link member and will pull the body portion of their own link closer thereto producing a chain with registering edges in diamond shaped contours of the adjacent arms closely drawn to one another, but still permitting a pivoted action between the adjacent links.

NICHOLAS NANASI.
